UNITED STATES PATENT OFFICE.

JOHN R. VAN TASSEL, OF GENEVA, NEW YORK, ASSIGNOR TO THE STANDARD OPTICAL COMPANY, OF GENEVA, NEW YORK, A CORPORATION OF NEW YORK.

LENS MOUNTING.

Application filed January 4, 1922. Serial No. 526,936.

To all whom it may concern:

Be it known that I, JOHN R. VAN TASSEL, of Geneva, in the county of Ontario, in the State of New York, have invented new and useful Improvements in Lens Mountings, of which the following, taken in connection with the accompanying drawings, is a full, clear, and exact description.

This invention relates to a lens mounting 10 to be used with rim or rimless lenses and refers more particularly to the construction of the nose-piece and its means of attachment to the rims or other lens-holders. These nose-pieces usually consist of bow-shaped strips of metal having their ends bent at an angle to the main body for convenience of fitting the bow to the nose and are attached by various fastening means to the lens-holders and in most instances, the 15 intermediate portion of the bow, which engages with the bridge of the nose, is slightly flattened to afford a broader surface of contact and, therefore, less imbedding effect with the nose but even under those conditions, the weight of the lenses and frame is sufficient to cause more or less irritation of the skin and flesh.

One of the objects of this invention is to provide the arch of the bow with a non-metallic sleeve of celluloid or equivalent more or less resilient material capable of being molded into a tube of more or less oval transverse exterior contour to enable it to conform more closely to the bridge of the 20 nose without irritation and at the same time to permit the metallic part of the bow to be made of uniform cross-sectional area and contour so that the non-metallic sleeve may be made as a separate article of manufacture 25 and slipped over and upon the metallic part, while the latter is in a straightened condition, thereby reducing the cost and greatly facilitating the manufacture of lens-mountings of this type.

Another object is to provide telescopic 30 connections between the ends of the nose-piece and lens-holders, whereby those parts may be easily and quickly connected and the telescopic parts bent to the desired angle 35 to facilitate the adjustment of the bow to the nose and also to serve as the means for holding the telescoping parts against relative endwise or turning movement one upon the other.

Other objects and uses relating to specific

parts of the mounting will be brought out in the following description.

In the drawings:

Figure 1 is a top plan of a rimmed lens-mounting embodying the various features of my invention.

Figure 2 is an enlarged top plan partly in section and partly broken away of the same mounting.

Figure 3 is a face view of the tubular metallic nose-piece with the non-metallic sleeve thereon before bending.

Figure 4 is a face view of parts of a mounting showing a rimless lens-holder with a straight tang before bending together with the non-metallic sleeve and a portion of the tubular metallic nose-piece.

Figure 5 is an enlarged transverse sectional view through the nose-piece taken on line 5—5, Figure 2.

As illustrated, this mounting may consist of a pair of lens-holding rims —1— as shown in Figures 1 and 2 or rimless lens-holders as —1'—, one of which is shown in Figure 4, each lens-holder being provided with a tang —2— rigidly united at one end thereto by spot welding or other suitable fastening means, said mounting also comprising a tubular metallic nose-piece —3— and a non-metallic sleeve —4— of celluloid or equivalent resilient material.

The tangs —2—, metallic nose-piece —3— and non-metallic sleeve —4— are preferably oval or slightly flattened in cross-section to prevent their turning one upon the other when assembled, the tubular member —3— being preferably of uniform cross-sectional area from end to end, while the sleeve —4— is slightly wider at the center and tapers toward both ends particularly along its greater diameter so as to form a relatively wider contact surface for the bridge of the nose to reduce liability of irritation thereof.

The parts —2—, —3— and —4— are assembled one upon the other telescopically while they are in a straightened condition or rather before bending to the required form so that after bending, they will be held against relative longitudinal movement by the bends and against turning movement by the oval formation thereof.

That is, after the metallic tube —3— and sleeve —4— have been brought to the required cross-sectional form and length and while still in a straightened condition, the

sleeve —4— is slipped endwise over and upon the tube —3— from one end to approximately the center thereof after which the intermediate portions of both of the assembled parts are bent transversely of their short axes into the form of a bow as shown in Figures 1 and 2, whereupon the tangs of the lens-holders —1— or —1'— may be inserted telescopically into the sockets in opposite ends of the tube —3— and afterwards bent to the required angle to bring the lens-holders into substantially the same plane, thereby establishing a positive lock between the tangs and adjacent ends of the metallic tube to hold the parts against relative endwise movement, while at the same time, the oval form of the tangs and adjacent ends of the tube —3— serve to hold the parts against relative turning movement, it being understood in practice that the tangs are of sufficient length to extend some distance beyond the angles as —a— formed by the last named bending operation and that the tubes preferably abut against the lens-holders —1— or —1'— as the case may be.

The tangs are of substantially the same cross-sectional area throughout the greater portions of their lengths except that their free ends are slightly tapered to permit them to enter more easily into the sockets in the adjacent ends of the tube, the cross-sectional area of the tangs being substantially equal to that of the sockets or opening through the tube to establish a close fit therein.

In like manner, the central opening through the sleeve —4— is of substantially the same cross-sectional area and form as that of the exterior of the tube —3— to cause those parts to fit snugly one upon the other when assembled, it being understood that by making the sleeve 4 of celluloid or equivalent material, it may be readily bent to the desired contour together with the bowed portion of the tube.

If desired, the sleeve may be additionally held against endwise movement by crimping its ends into circumferential channels —5— in the periphery of the adjacent portion of the tube although this provision is deemed unnecessary in view of the bending of the two parts to form the bow-shaped nose-piece but in either case, the ends of the sleeve and also the ends of the tube may be tapered off gradually to merge as nearly as possible with the adjacent portion of the tube and lens-holder, respectively.

What I claim is:

1. In a lens-mounting, a tubular nose-piece, and lens-holders having tangs inserted telescopically in the ends of the nose piece, the telescoping parts being bent to form similar angles.

2. In a lens-mounting, a tubular nose-piece, and lens-holders having tangs inserted telescopically in the ends of the nose-piece, the telescoping parts having cooperative means for holding them against relative rotation one upon the other.

3. A lens-mounting comprising a tubular nose-piece, a sleeve surrounding the intermediate portion of the nose-piece, and lens-holders having tangs inserted telescopically in both ends of the tubular nose-piece.

4. A lens-mounting comprising a tubular nose-piece, a sleeve surrounding the intermediate portion of the nose-piece, and lens-holders having tangs inserted telescopically in both ends of the tubular nose-piece, the nose-piece, sleeve, and tangs being slightly flattened transversely to prevent relative rotation of those parts one upon the other.

In witness whereof I have hereunto set my hand this 19th day of December, 1921.

JOHN R. VAN TASSEL.
